(57) **CLAIM**

The ornamental design for a chalk reel, as shown and
described.

DESCRIPTION

FIG. 1 is a perspective view of a chalk reel embodying the
new design, illustrated with surface shading;

FIG. 2 is a first side view of the chalk reel shown in FIG. 1.

FIG. 3 is a second side view of the chalk reel shown in FIG.

1.

FIG. 4 is a third side view of the chalk reel shown in FIG.

1.

FIG. 5 is a fourth side view of the chalk reel shown in FIG.

1.

FIG. 6 is a fifth side view of the chalk reel shown in FIG. 1.

FIG. 7 is a sixth side view of the chalk reel shown in FIG.

1.

FIG. 8 is perspective view of the chalk reel of FIG. 1,

illustrated using a wire frame drawing technique.

FIG. 9 is a first side view of the chalk reel shown in FIG. 8.

FIG. 10 is a second side view of the chalk reel shown in FIG.

8.

FIG. 11 is a third side view of the chalk reel shown in FIG.

8.

FIG. 12 is a fourth side view of the chalk reel shown in FIG.

8.

FIG. 13 is a fifth side view of the chalk reel shown in FIG.

8; and,

FIG. 14 is a sixth side view of the chalk reel shown in FIG.

8.

1 Claim, 12 Drawing Sheets
